UNITED STATES PATENT OFFICE.

ALBERT E. CRANSTON, OF SPOKANE, WASHINGTON, ASSIGNOR TO ALEC J. GERRARD,
OF CHICAGO, ILLINOIS.

BINDING MACHINE.

Application filed October 26, 1922, Serial No. 597,824. Renewed June 16, 1927.

This invention relates to improvements in binding machines for binding bunches of loose integers such as box shooks or other similar material, or previously nailed up 5 boxes or fixed entities.

One of the features of this invention is to provide an upwardly inclined table along which the integers are propelled in edgewise relation against the table.

10 A further feature resides in means whereby the operator may pick up a bunch of loose shooks lying flatwise, and deposit the bunch flatwise in the machine, said means functioning to turn the bunch into edgewise engagement with the table, thereby avoiding the necessity of the feed operator manually exerting himself to turn the bunch from a flatwise to an edgewise position.

15 A further feature consists in an improved compressing means whereby the bunch of loose integers is compressed as it advances, and is held under compression until the binding wire is tied, whereupon the pressure is withdrawn and the bound bundle proceeds toward a delivery position.

20 A special feature of the bunch compressor resides in its elasticity of operation whereby bunches of various dimension may be compressed with equal facility and without alteration or adjustment of the compressor, the latter being of a floating type and being 25 actuated by gravity.

25 A further feature consists in providing means whereby the gravity actuation is supplemented by an additional and preferably elastic stress on the compressor whereby a small bunch may be compressed to the same extent as a large bunch.

30 In depositing a loose bunch of integers in the machine, it frequently happens that the ends will be irregular due to the fact that the shooks get out of accurately stacked relation, and it is a feature of my invention to provide "slappers" or aligners for aligning the ends of the bunch, preferably, just prior to advance of the bunch along the table, whereby the finally bound bundle will be substantially rectangular, instead of irregular, in form.

35 My invention includes an endless carrier or carriers having upstanding bundle advancing arm devices or followers for advancing the loose bunches or bound bundles upwardly along the table, and it is a feature 40 of this invention to provide track and shoe

means whereby said followers will be retained against wobbling and be held to position both as regards the active and the inactive laps of travel of the carriers.

45 My invention has many other features and objects which will be more fully described in connection with the accompanying drawings and which will be more particularly pointed out in and by the appended claims.

In the drawings:—

50 Fig. 1, is a view in side elevation looking from the right of the machine, and with the compressor in a withdrawn position.

55 Fig. 2, is a similar view with part omitted showing the compressor in a functioning position.

60 Fig. 3, is a similar view, with certain parts omitted, showing the compressor in readiness to compress an approaching loose bunch of integers and illustrating how various size 65 bunches may be compressed.

65 Fig. 4, is a view looking from the left-hand side of the machine.

70 Fig. 5, is a view looking from the right of Figure 1, and directly at the face of the 75 table, this view being on a slightly increased scale with respect to Figure 1.

75 Fig. 6, is a sectional view on line 6—6 of Figure 1, showing the main wheel and main shaft.

80 Fig. 7, is a face view of the main wheel showing the manner of alternately actuating the transmission means to the endless carriers and the knotting mechanism.

85 Fig. 8, is a detached view of the main 90 wheel, looking in the same direction as in Fig. 7.

90 Fig. 9, is a view of the same looking in a direction reverse to that shown in Fig. 8.

95 Fig. 10, is a sectional view on line 10—10 of Fig. 2 illustrating a plan view of the compressor.

100 Fig. 11, is a view of certain gearing looking from the left of Fig. 2, as indicated by the arrow.

105 Fig. 12, is an enlarged sectional view on line 12—12 of Fig. 2.

Fig. 13, is a view in side elevation of the lower or intake end of the table, and showing a bunch of loose integers deposited flatwise on the rocking frame.

Fig. 14, is a similar view showing how the frame has been rocked.

Fig. 15, is a skeleton contracted view showing the track guiding means for the pusher

arm shoes and only showing enough of the arms to illustrate the connection.

Fig. 16, is a sectional view on line 16—16 of Fig. 15.

5 Fig. 17, is a sectional view on line 17—17 of Fig. 15.

Like characters of reference designate similar parts throughout the different figures of the drawings.

10 As illustrated, my machine comprises a main frame including sides 1 and 2, suitably connected and preferably mounted on a wheeled base 3, as shown in Fig. 4. A main shaft 4, is journaled in the sides 1 and 2, and mounted thereon is a main wheel 5 having gear teeth 6. A pinion 7, on counter shaft 8, (Fig. 11) also journaled in the frame sides, is in continuous mesh with teeth 6, and this shaft 8, carries a gear 9, meshing with gear 10, on power shaft 11. A pulley 12, on shaft 11, is driven through any suitable source of power which is not necessary to show.

25 The main frame is provided with an upwardly inclined table designated as a whole at 13, and comprising spaced sections 14, extending from the lower or intake end 15 to the upper or delivery end 16. A gravity delivery chute 17, extends from the upper end 16. Between the sections 14, two endless carriers preferably in the form of chains 18, are disposed. These endless chains 18 are trained over chain wheels 19, mounted on shaft 20, at the top, and over chain wheels 21, mounted on shaft 22, at the bottom. Shaft 20 also carries a chain wheel 23, over which a chain 24, is trained, the opposite bight of which is trained over wheel 25, mounted on shaft 26. A wheel 27, on shaft 26 transmits through chain 28, to chain wheel 29, on shaft 30, see Fig. 6. The foregoing will hereinafter be termed the carrier transmission means and I will later describe the manner in which power is transmitted 40 from main wheel 5, to drive the carriers or chains 18.

50 I have shown, generally, the mechanism of a knotter, together with a needle arm, to illustrate the location and relation of this part of the mechanism to my machine, but as I will not specifically claim the same, but only broadly refer to it in the claims, I do not deem it necessary to enter into a detailed description of its structure and operation, as 55 both will be described and claimed in a separate application. However, there are specific features as regards the means of operating the knotter, in certain relation to the operation of the chains 18, which I will 60 claim hereinafter. Therefore, I will describe enough of the knotter to provide a foundation for claims broadly to "knotting mechanism."

65 As shown in Figures 4 and 5, 31 designates a knotter structure which is disposed

in the path of the material and midway between the intake and discharge ends of the table 13. It will also be noted that this knotter structure is between the chains 18. A hook 32, operated by a rod 33, serves to advance the wire into the slot 34. Rod 33, is connected with arm 34, on shaft 35. An arm 36, on shaft 35, (see Fig. 4) is connected by rod 37 with arm 38, on shaft 39. Periodically, a cam 40, on main wheel 5, (see 75 Figs. 6 and 9) lifts arm 38, holding it elevated for the proper period, and then releases this arm, under the action of a spring 41, (see Fig. 4). A needle arm 42, having an L-shaped extension 43, is mounted on shaft 44, journaled in bearings 45, carried by brackets 46. An operating arm 47, on shaft 44, is connected by rod 48, with a cam roller arm 49, (Fig. 4) mounted to swing about a stud 50. A roller 51, travels in a 80 closed cam path 52, of a cam 53, on main shaft 4, whereby the needle arm is actuated in proper synchronism with the knotter 31. Sheaves 54, 55, 56 and 57, form the path along and about which the binding wire 90 travels. A shaft 58, serves to rotate the knotter and has beveled gear 59, meshing with beveled gear 60, on shaft 61. Mounted on shaft 61, (see Fig. 1) is a sprocket 62, over which chain 63, is trained. The opposite bight of chain 63 is trained over sprocket wheel 64, on stud shaft 65, (see Figs. 1, 6 and 7).

Now it will be clear that I have shown and described knotter operating means driven from shaft 65, needle arm operating means driven by cam 53, and knotter hook operating means driven by cam 40.

Reference will next be made to my improved loading mechanism whereby loose 105 bunches of shooks are deposited in edgewise relation against the table sections 14, attention being directed more particularly to Figs. 1, 2, 5, 13 and 14.

110 My improved loading mechanism comprises two rocking frames, disposed laterally of carrier chains 18, and united to operate in unison but as they are alike in construction and operation only one need be described in detail, and that upon the left of Fig. 5, will now be described. A bracket 66 on frame side 1, fixedly journals a supporting rod 67, at its outer end. A bracket 68, fixed to frame member 69, supports the inner end of rod 67. This section of the rocking frame comprises a supporting foot 70, for the shooks, and an outer connecting member 71. A rod 72, connects the member 71 and the foot 70, making a rigid frame. A bar 73, is rigidly connected with the bottom of foot 70 and member 71. A link 74, pivoted to said bar, is connected with lever 75 (see Fig. 7). This lever 75 is pivoted at 76, to a standard 77, mounted on bar 3. 115 The inner end of said lever 75 carries a 120

125 130

roller 79, adapted to be actuated by cam 80, on wheel 5. Cam 80 has an initial terminal 81, for running up on roller 79, and as the roller rides on cam 80, the rocking frame is tilted toward the table 14, as shown in Fig. 14, and when the cam 80, releases said roller 79, the rocking frame returns to a receiving position, as shown in Fig. 13. To insure this return movement, I employ a spring 82, the upper end of which is secured to member 71, and the lower end of which is connected with a bracket 83 (see Fig. 1). To prevent the frame from rocking too far toward the position shown in Fig. 13, I provide a stop 84, in the form of an adjustable bolt threaded in a stop bar 85, which is mounted on brackets 66 and 68. Now the foot 70, forms the horizontal supporting member for the shooks A, in the position shown in Fig. 13. I also provide a support, angular to, and preferably at right angles to the foot 70, to engage the side edges facing the table 14. This takes the form of an upstanding support 86 which is of sufficient height for shooke bunches of a relatively wide range of size. Now it will be clear that when the frame is in the receiving position shown in Fig. 13, the shooks are supported on the bottom by foot 70 and along the table side edge by support 86. I cut away the table section 14, at 87, Fig. 5, so that when the frame is rocked into a depositing position, as shown in Fig. 14, the right hand edges of the bunch A will be disposed in edgewise engagement against the table and the left hand face of support 86, looking at Fig. 13, will be flush with the table. In order that the two frame sections may be actuated in unison, the supports 86 are connected at 87'. As a matter of safety, I provide each foot 70, with a guard 88, and these guards are connected by a bar 89. Between the two rocking frames, I prefer to dispose a fixed foot 90, so that in case the operator does not accurately deposit a short bunch of shooks so that one of each of the ends will rest on one of the feet 70, this fixed foot 90 would prevent the loose shooks from falling down on the floor. It will be noted that the bunch or bundle advancing arm devices with which each chain 18 is provided, and which will be later described, will advance from below and between the rocking frame sections into engagement with the bottom of the bunch of loose shooks and advance the latter upwardly along the table.

Now having described the structure of my improved loading mechanism, which comprises the companion rocking frames, I will next point out its advantages.

In the first place, these loose shooks are stacked flatwise on the floor of the mill. If they were stacked edgewise they would fall about in utter disorder. Now when an operator picks up a bunch, he picks it up flat-

wise, with his fingers engaging the flat bottom of the lowest board of the bunch. With this improved construction, the operator merely deposits the loose bunch flatwise on the feet 70, with the inner edge portion in engagement with supports 86, and he does not have to turn the bunch over ninety degrees, as he would have to do if the table were horizontally disposed, and if I had not provided this improved loading mechanism. Therefore, it will be seen that by relieving the operator of the work and strain of holding and turning a loose bunch of shooks every time he deposits them, and providing a natural method of easy deposit of the shooks, I have accomplished a labor saving feature that greatly speeds up the work of feeding a binding machine. Now it will be understood that a bunch of loose integers cannot be as tightly bound when resting flatwise against the table along which it is being advanced, as when the bunch rests edgewise thereagainst. Hence, to all practical intents and purposes, it is essential that the loose shooks rest edgewise against the table, and therefore, the idea of an inclined table, together with a rocking loading mechanism, jointly contribute to a very marked improvement in this art.

When the loose shooks are placed upon the feet 70, the end edges of the shooks of the bunch may be out of alignment thereby giving the bunch an irregular form. This cannot be true of that side of the bunch facing the table, as the upright members 86, serve also as aligners, but it is desirable to have the shooks in aligned relation endwise of the bunch so that the bunch, when bound into a bundle, will have a substantially rectangular form. By having the bundles of regulation size, they take up less room in storage and less shipping space. Therefore, I have a "slapper" or aligning mechanism which I will now describe in detail.

Slapper or aligning plates 91 are disposed on opposite ends of the bunch to be deposited on feet 70, both plates and their accompanying mechanism being the same, only one will be described in detail. A supporting arm 92 is provided with bosses adjustably fixed on rods 67 and 72 so that said arm may be adjusted toward or away from chain 18, according to the length of shooks to be bound. Links 93 are pivoted at 94, to plate 91, and at 95 to arm 92. When the loading mechanism is in the receiving position shown in Fig. 13, the plates 91 are in a retracted position, to permit the shooks to be freely deposited on the rocking frame. As the frame rocks into the position shown in Fig. 14, the plates 91 are moved toward and into impact engagement with the ends of the shooks to line up the latter. I will next describe the means for actuating said plates 91. As shown in Figs. 2 and 5, a rod 96 is pivotally

connected with the lower front corner of plate 91 and said rod extends downwardly through a bracket 98, mounted on stop bar 85, which, as previously described, is supported on brackets 66 and 68. On the lower end of said bar is a stop nut 99, between which and the end of the bracket 98, is interposed an expansively acting spring 100. Now by reason of the fact that arm 92, is mounted on rods 67 and 72, said arm will rock with said rocking frames and hence when said frames are in the position shown in Fig. 14, the springs 100 will be under tension and will exert a quick but yielding down thrust on plates 91, causing said links 93 to move toward the horizontal and slapping the plates 91 sharply against the ends of the shooks. This action occurs just as the rocking frames assume the position shown in Fig. 14, and before the advancing means engages the bottom of the bunch. In fact, these plates 91 may complete their function just before the side edges of the shooks reach an engaging position with the table sections 14 so that they will not have to overcome any friction except that due to the weight of the shook boards on each other. Thus, just before the bunch of shooks is in the position shown in Fig. 14, it will be in symmetrical form for binding. An important feature of this action resides in the fact that it is yielding, not positively imparted. A positive action on plates 91, would not only require a very accurate adjustment of the arms 92 and if for any reason, a shook happened to be too long, then either stoppage or breakage would inevitably occur. I will next describe the manner in which the plate 91 is restored to a retracted position when the rocking frames are returned to the receiving position shown in Fig. 13.

I provide the rod 96, with a stop nut 101 which is adapted to engage with the top of bracket 98 before the rocking frames reach the receiving position shown in Fig. 13, thereby imparting an upward thrust on the rod 96 for elevating the plate 91 to the retracted position. Thus when the plates 91 are spread apart, full ingress is afforded for depositing a bunch of shooks onto feet 70.

I will next describe the means for advancing the loose bunches of shooks upwardly from the rocking frames along the table sections 14, referring first to Figs. 15 to 17.

The endless chains 18 carry bunch and bundle advancing devices or followers in pairs suitably spaced apart and each follower, which I will broadly designate at C, comprises a bundle pushing member 102 and a supporting member 103 pivotally connected at 104. These are specifically old but I have devised a novel means for preventing said devices from wobbling either during their active or inactive laps of travel. It will be understood that if these devices

were permitted to wobble, they would not uniformly engage the loose shooks, and during their return or inactive laps of travel, they would interfere with other portions of the machine and thereby prevent a compact arrangement of mechanism. It is also a feature during the active laps of travel, to prevent the followers and their chains from being lifted away from the table.

Each of said members 102 and 103 is pivoted to a shoe 105 and 106, and as both are the same in construction and operation, only one will be described in detail.

Shoe 105 is in two separate halves which are united by the pivot 107 which connects the shoe with said member 102. The shoe halves are grooved at 108 to receive the chain 18, which is rigidly secured thereto, whereby the two halves are rigidly united. Said halves 105 are also grooved at 109 for engagement with a guide rail of T-form which is indicated as a whole at 110 and which extends from the intake to the delivery end of the table on the active lap of travel of the carriers. Said rail has a top portion 111, the outer edges of which engage the grooves 109, and also a base portion 112. Now the shoe halves extend into engagement with the base portion 112, as indicated at 113. A web 114, unites the top portion 111 with the base portion 114. With this double surface engagement, the shoe 105 is very effectively held in engagement and affords a greater wearing surface than would be afforded by a single rail engagement, which is necessary on the active lap, because of the strain imposed in advancing the material. A further feature of the double or T-form rail 110 is that the top portions present top faces 115 on which the chains 18 ride, as well as affording a double guiding engagement for the shoes.

On the inactive lap of travel, I provide a single rail 116 by reason of the fact that the arms 102 and 103 are not subjected to any stress and it is merely desirable to retain the arms from wobbling. As seen in Fig. 17, the grooves 109 engage the side edges of the rail 116, the portions 113, being free from engagement, with any rail surface. As the shoes enter their active lap of travel when rounding wheels 21, they first engage strip guides 117 which terminate at 118 at the lower ends of rails 110. The faces 113 ride onto these guides 117 and the latter register the shoes with rails 110. At the upper ends 119, the rails 110 terminate in free ends and the shoes slide from the latter and traverse wheels 19. Before the shoes leave wheels 19, they are engaged by strip guides 120 which guide the shoes into registry with rails 116. The lower ends 121 of rails 116 are free and the shoes slide from the latter and traverse wheels 21. It will be understood that sprocket wheels 19 and 21 are designed

with sufficiently long teeth to take care of the projection of the shoes 105, this projection being exaggerated in the drawings for purpose of clear illustration. The shape of 5 rail 116 is clearly shown in Fig. 1, illustrating how, on the inactive lap, the advancing means is guided past and about shaft 61, which would be impossible if the chains 18 were not guided on this lap.

10 Now it is old, in machines of this character to run these chains in channel guides, or more comprehensively speaking, to guide these chains by reason of the chains actually engaging the guides. However, this alone 15 would not prevent the arms from wobbling, as I have found in actual practice. In this construction, I provide means for positively guiding the shoes themselves, and because the chains are secured to the shoes, the chains 20 are necessarily guided but not as the primary agency. These chains, in the absence of this improvement might be very successfully guided so that their lateral sway or turning action would be nugatory, and yet even a 25 minute sway or turn of the chain, would, because of the extent of projection of the arms therefrom, result in a very material sway of said arms. Now by applying the guiding means directly to the shoes, instead of the 30 chain, I entirely avoid any objectionable sway of the arms, and I believe this to be new.

A bunch of shooks, shingles or lath, while made up of integers which, individually are 35 incompressible, relatively speaking, are not incompressible when assembled in bunches, but on the contrary, they are susceptible of very material compression to obtain a bound bundle that is compact and firm. Furthermore, it is an object of this invention to bind 40 bunches of various sizes, and obtain uniform compression irrespective of the size of bundle within practical limits, and it is to the performance of this function that I have addressed a compression mechanism which I 45 will now describe in detail.

A pair of track bars 122, Figs. 2 and 10, have their lower ends mounted to swing about shaft 22, as an axis, and said bars extend 50 upwardly to near the top of the machine, as shown. Of course said bars 122 will be rigidly connected with each other to swing or be swung in unison. A cam operated arm 123, is preferably rigidly connected with both of said bars and carries a roller 124 at its free end. A cam 125, mounted on main shaft 4, serves to rock said track bars 122 toward the table 14. A compressor 55 126 is rigidly mounted on a carriage 127 and has rollers 128 which engage said track bars 122 as the carriage travels longitudinally thereof. A lever arm 129 has one end pivoted to said carriage at 130 and its other end is pivoted at 131 to a supporting link 132, 60 which latter is pendently pivoted on the

machine frame at 133. Cushioning means is connected with said lever arm and as shown, said means includes a cylinder 134 which is pivotally connected at 138, with said lever arm 129. A suitable quantity of 70 oil or other liquid is disposed in cylinder 134 to act as a cushioning medium. A pipe 139 opens at 140 and 141 to opposite ends of said cylinder and a regulating valve 142 is interposed in said pipe. The purpose of this 75 valve is to restrict the flow of oil in response to movement of the piston 136.

The operation of said compressor is as follows:—

Referring to Fig. 3, the bunch B, has been 80 bound in bundle form and is being advanced upwardly toward the delivery chute 17. The loose bunch A, is approaching the knotter and it will be seen that its dimension on a line parallel with the table 14, is much greater than a corresponding dimension of bound bundle B, the difference being exaggerated for purposes of graphic illustration. Now the cam 125 has rocked the track bars 122 toward the table 14 to project the compressor 126 into the path of loose bunch A. Right here, it is pertinent to point out that this projection of the compressor is timed sufficiently early so that it will be in the path of an approaching loose 90 bunch, irrespective of the height of said bunch (within limits), and without any special adjustment of the compressor mechanism when greater or less size bunches are being bound. This is an important feature 100 of my improved compressor. Now, reverting back to the description of operation, it will be clear that in Fig. 3, piston 136 has moved downwardly to the bottom of cylinder 134, thereby forcing the oil or cushioning medium below the piston outwardly and upwardly through pipe 139 into the space above piston 136. Further, piston 136 is supporting compressor 126, in the position shown in Fig. 3. Now as bunch B approaches and engages compressor 126, the latter will be elevated and will longitudinally traverse track bars 122 into the position shown in Fig. 2. Now the weight of the compressor and carriage 127, combined, 110 will be imposed on the loose bunch to compress the same. However, in addition to this weight, the consequent upward movement of piston 136, as a result of this elevation of the compressor, will have forced the oil to pass from above piston 136 downwardly to the space below said piston, through pipe 139. Now valve 142 will be adjusted to retard the flow of oil to exert 115 a resistance to such elevation of the compressor 126, in addition to the weight of the latter, sufficiently to effectively compress the loose bunch to the required degree of compactness. Then, when pressure is released, the integers of the bound bundle 120 125 130 135 140 145 150 155 160 165 170 175 180 185 190 195 200 205 210 215 220 225 230 235 240 245 250 255 260 265 270 275 280 will consequently expand, and the wire will tightly bind the bundle. Now it will be clear that the weight of the compressor on a loose bunch will always be the same, irrespective of the size of the bunch. Further, it will now be clear that the added resistance of the oil, will always be the same, irrespective of the size of the bundle, and without requiring even a special adjustment of valve 142, because of the difference in size of the bunches. This is a very important feature of my compressor.

Now the compressive action of the compressor 126 is constant and uniformly sustained from the time it is first engaged by the loose bunch until it is released by withdrawal therefrom. Thus it will be seen that because the pressure is uniform, it is not cumulative and does not increase as the bunch ascends, if it did, then the pressure on different sized bunches would vary in accordance with the size, and such a device, would require adjustment for each different size bunch. The reason why this additional pressure exerted by the oil is uniform, is that the valve 142 retards the initial quantity of oil seeking passage therethrough with the same resistance as the last quantity, and when the cylinder 136 is full, or substantially so, as it will be in practice, the slightest movement of the piston 136 will fully take up any slight oil slack, and just as soon as this slack has been taken up, then resistance to further passage or movement of the oil, responsive to piston movement will be a uniform resistance, throughout the movement of the compressor in an upward direction.

Now when the bunch B, has reached the position shown in Fig. 2, the chains 18 stop, in order to permit the needle arm 42 and the knotter mechanism 31 to bind and tie the wire. A pawl and ratchet wheel (not shown) may prevent backing down of the chain. I will broadly designate this as the binding period of rest. Immediately after the knot is tied, the cam 125 releases the track bars 122 for retractive rocking movement by gravity back to the position shown in Fig. 1. This withdraws the compressor from engagement against the bound bundle, preferably just before the chains 18 are again actuated. Now it will be clear that piston 136, at the start of this withdrawal movement of the compressor, is at the top or in an upwardly advanced position in the cylinder 134, and that when the compressor 126 is freed from engagement with the bound bundle B, it would, with its carriage 127, be free to travel downwardly on track bars 122, by gravity. However, the oil now in the bottom of the cylinder 134, resists downward movement of the piston 136 and consequently the lowering of the compressor is retarded and cushioned toward the pis-

ton shown in Fig. 1. I have now described a complete cycle of operation of my improved compressor and it will now be clear that as upward movement of the latter is dependent on the movement of the bunch actuating it, and as it has no prescribed and definite mechanically controlled movement which is always uniform, that the compressor is clearly a floating element. In practice, and in order to take the stress off from piston 136 when the machine is idle, and if desired when in operation, I employ a bumper rest as shown at 143. I find that the carriage, in practice, is very gently lowered against the bumper.

I will next describe the manner in which transmission is effected from main wheel 5, to operate the various mechanisms.

Shaft 30, is journaled in a box 144 which is slidable in housing 145, in frame side 1. A spring 146 normally acts to shift box 144 to the right of Fig. 6. A strap bearing 147, mounted on frame side 1, also journals shaft 30. On the outer end of shaft 30, is the sprocket wheel 29. On the inner end of shaft 30, is a mutilated pinion 148, the teeth of which are adapted to mesh with the teeth of a segment 149, on gear wheel 5. A cam 150, concentric with shaft 4, forms a continuation of segment 149, making a complete circular path. Pinion 148, has on its inner end, a smooth arcuate face 151, adapted to engage cam 150, which permits rotation of the latter and holds pinion 148 against rotation. This cam 150 does not project from the face of wheel 5, as far as segment 149, as seen in Fig. 6, and hence when the segment passes pinion 148, its arcuate face 151 engages cam 150 and has sliding engagement therewith until the teeth of segment 149 again reach pinion 148. Thus, it will be seen that while main wheel 5, rotates continuously, while the machine is in operation, it only drives pinion 148 while the latter is in mesh with segment 149, consequently, pinion 148 is intermittently driven. I have previously described the transmission from sprocket 29, to sprocket 23, (Fig. 1) which thus completes the description of the carrier operating means.

I will next describe the manner whereby the knotter operating means is intermittently driven from wheel 5, in alternation with the carrier operating means.

Referring to Fig. 6, shaft 65, carries on its inner end a mutilated pinion 152 having a mutilated or cam engaging peripheral portion 153 for engagement with cam 150. A box 154, is slidable in guide 155, in frame side 1, and journals shaft 65, and is urged by spring 156, to the left of Fig. 6. A strap bearing 157 journals the outer end of shaft 65. I have shown, in Fig. 7, the pinion 152, in engagement with cam 150, and in this position of wheel 5, the knotter

is at rest. When the segment 149 reaches pinion 152, the latter will be in mesh with the teeth of said segment and the knotter will be actuated and the carriers will be at rest. I have already described the means for transmitting rotary motion from shaft 65 to shaft 61 (Fig. 1).

It will now be clear that when the carriers are advancing a bunch of shooks toward the knotter, the latter will be at rest, and when the shooks are in a position to be knotted, the carriers will be at rest and the knotter will be actuated. In Figs. 1 and 7, it is clear that while the knotter is being actuated, the lever 75 will be actuated to rock the bunch receiving frame from the position shown in Fig. 13, to that shown in Fig. 14, in readiness for the followers when the carriers next start.

If, as in some sizes of shooks, the latter are of such dimension that the bunches will not pass under the needle arm when disposed edgewise against the table, they can be disposed flatwise thereagainst, although in this disposition the tied bundles will not be compressed as the compressor cannot apply compression edgewise of a bunch. However, this contingency is rare.

While this machine is primarily designed for use in binding loose integers, it is also adapted for use in binding nailed boxes for foreign transit, or for binding anything in the form of separate articles, either individually compressible or not, which have a definite form, in contradistinction to hay or rags in loose bulk prior to baling, which are formless.

In many respects, I gain very appreciable advantages from inclining the table upwardly but I do not wish to be limited to an upwardly inclined table, as the pressure device with spring return, and the rocking frame, would each be of great utility in a machine wherein the table was not upwardly inclined.

While I have shown one form of my invention, I do not wish to be limited thereto except for such limitations as the claims may import.

I claim:

1. A binding machine comprising means for advancing a bundle of loose integers in an upward direction, and mechanism for compressing said integers irrespective of size thereof.

2. A binding machine comprising means for advancing loose integers in an upward direction, and gravity actuated mechanism for compressing said integers on the upward travel thereof.

3. A binding machine comprising means for advancing loose integers in an upward direction, and retarding mechanism for compressing said integers on the upward travel of the latter.

4. A binding machine comprising means for advancing loose integers in an upward direction, and combined gravity actuated mechanism and retarding mechanism for compressing said integers while the latter are ascending.

5. A binding machine comprising means for advancing loose integers upwardly and then holding them for a period of rest and then continuing to advance the same, and compression mechanism movable into the path of and compressing said integers prior to and during said period of rest and thereafter releasing said integers.

6. A binding machine comprising means for advancing a loose bunch of integers upwardly and then holding them in a position of rest for a period and then continuing the advancing movement of said integers along the same line of travel, and compression mechanism movable into the path of said integers and compressing the same and then moving out of the path of said integers to permit the latter to continue their advancing movement.

7. A binding machine comprising means for advancing a loose bunch of integers in an upward direction, and compression mechanism movable into the path of said integers relatively greatly in advance of the latter whereby integer bunches of widely varying size may be compressed.

8. A binding machine comprising means for advancing a loose bunch of integers in an upward direction, and compression mechanism having operating means movable through a fixed cycle and provided with a bunch compressor operable to an extent dependent upon the size of the bunch.

9. A binding machine comprising endless means for advancing bunches of loose integers in an upward direction with a periodic rest at a binding location, a track bar with means for oscillating the latter about a fixed axis toward and from the path of travel of said bunches, and a compressor slideable on said track bar for compressing said bunches.

10. A binding machine comprising means for advancing a bunch of loose integers in an upward direction, and a gravity compressor coacting with said means and advanced by said bunch to compress the latter.

11. A binding machine comprising means for advancing a bunch of loose integers along an upward incline, a track bar pivoted to swing about a fixed axis at its lower end, means for swinging the upper end of said bar toward and from the path of travel of said integers, a compressor slideable longitudinally on said bar for engagement by said integer bunches to compress the same, an arm having pivotal connection with a supporting link at one of its ends and having its remaining end pivoted to said com-

pressor, and means connected with said arm between its ends for resisting upward movement of said arm to increase the compressive action of said compressor.

5. 12. A binding machine comprising means for advancing a loose bunch of integers along an upward incline, a compressor, means for moving said compressor into the path of an advancing bunch to be engaged 10 and be elevated by the latter to compress the same and then quickly withdrawing said compressor from engagement with said bunch, and means for increasing the compressive action of said compressor and cushioning the withdrawing movement of the latter.

13. A binding machine comprising means for advancing a bunch of integers along an upward path of travel, and a floating 20 compressor for compressing integer bunches of different dimensions.

14. A binding machine comprising an upwardly inclined table, means for advancing bunches of loose integers upwardly along 25 said table, a rocking frame at the lower end of said table adapted to occupy a receiving position to support a bunch of loose integers, and means for rocking said frame to dispose said integers against said table and into the 30 path of said advancing means whereby said integers may be advanced upwardly along said table.

15. A binding machine comprising an upwardly inclined table, endless means for advancing bunches of loose integers upwardly along 35 said table, a rocking frame having angularly disposed members for supportingly engaging two sides of a bunch of loose integers, spring means normally holding said 40 frame in a position to horizontally receive a bunch of loose integers, and means for rocking said frame to dispose said integers against said table and into the path of said endless means whereby said integers may be 45 advanced upwardly along said table.

16. A binding machine comprising an inclined table and means for advancing loose integer bunches upwardly along said table, said table having cut away portions, a rocking 50 frame having subjacent supporting members and upstanding members of a height to receive bunches of different sizes, means normally holding said frame with said supporting members horizontally disposed and said upstanding members vertically disposed to receive a bunch of integers, and means for rocking said frame to project said upstanding members into said cut away portions and flush with said table with one 55 side of said bunch in engagement therewith and said supporting members inclined and at right angles to the plane of said table thereby disposing said bunch in the path of said advancing means.

17. A binding machine comprising an up-

wardly inclined table, bunch advancing means movable upwardly along said table, a rocking rack for deposit of loose integer bunches therein, alining plates mounted on said rack to move toward and away from the ends of the bunch thereon, means for rocking said rack into a bunch delivering position with respect to said table, and mechanism actuated upon such rocking movement of said rack for moving said plates into engagement with the ends of said bunch to aline the end edges of the integers thereof. 70 75

18. A binding machine comprising an upwardly inclined table, endless chains having active laps running upwardly along the top of said table and in-active laps running below said table, wheels at the lower and upper ends of said table about which said chains are trained, tracks extending along the active laps of said chains and tracks extending along the in-active laps of said chains, bundle advancing arm devices carried by said chains and in sliding engagement with said tracks whereby said devices 80 85 will be held in projecting positions throughout their endless travel.

19. A binding machine comprising an upwardly inclined table, endless chains having active laps running upwardly along the top of said table and in-active laps running below said table, wheels at the lower and upper ends of said table about which said chains are trained, tracks extending along the active laps of said chains between said upper and lower wheels, tracks extending along the in-active laps between said upper and lower wheels, bundle advancing devices pivoted to said shoes and engaging said tracks, and devices for guiding said shoes 90 95 onto said tracks at the upper and lower ends. 100 105

20. A binding machine comprising an upwardly inclined table, means for advancing bunches of integers upwardly along said table, a track bar, a compressor for said 110 bunches movable along said bar, and means independent of said bar for limiting longitudinal travel of said compressor along said bar.

21. A binding machine comprising an upwardly inclined table, means for advancing bunches of loose integers upwardly along said table, a track bar, a compressor for said bunches movable along said bar, and cushioning means for limiting travel of said compressor along said bar. 115 120

22. A binding machine comprising an upwardly inclined table, means for advancing bunches of integers upwardly along said table, a track bar, a compressor for said 125 bunches movable along said bar, and means limiting downward movement of said compressor and resisting upward movement thereof.

23. A binding machine comprising an up-

- wardly inclined table, an endless carrier for advancing bunches of loose integers upwardly along said table, knotting mechanism between the end of said table and in the path 5 of travel of said bunches, power transmission means for said carrier, power transmission means for said mechanism, and driving means for alternately operating said carrier and mechanism.
24. A binding machine comprising a table, a movable receiving device for a loose bunch of shooks, and means for actuating said device to deposit said shooks in edge-wise engagement with said table.
25. A binding machine having a table provided with tracks, and bundle advancing arm devices movable along said table and having 10 slidable engagement with said tracks.
26. A binding machine having a table provided with tracks, chains riding on said tracks, and bundle advancing arm devices connected with said chains to be advanced thereby and having sliding engagement with 15 said tracks to hold said devices and chains in position.
27. A binding machine having a table provided with tracks of T-cross section, chains riding in contact on the top faces of said tracks, and bundle advancing arm devices 20 connected with said chains to be advanced thereby and having shoes in slidable and retaining engagement with the top and bottom flanges of said tracks.
28. A binding machine having a table pro-
- vided with tracks having upper and lower 35 flanges, chains riding on top of the upper flanges, and bundle advancing arm devices connected with said chains to be advanced thereby and having shoes provided with grooves for engagement with the edges of 40 the upper track flanges and said shoes having flat portions in slidable engagement with the faces of said lower flanges.
29. A binding machine comprising a table, a rack for receiving an entity in one position, 45 and means for rocking said rack to dispose said entity against said table in another position.
30. A binding machine comprising means for advancing an entity of material in one 50 direction, and retarding mechanism for compressing said material.
31. A binding machine comprising means for advancing an entity of material, and a floating compressor mechanism for compressing 55 said material.
32. A binding machine comprising means for advancing an entity of material and then holding it for a period of rest and then again advancing the same, and compression mech- 60 anism movable into the path of and compressing said material prior to and during said period of rest and thereafter releasing said material.

In testimony that I claim the foregoing as 65 my own, I hereby affix my signature.

ALBERT E. CRANSTON.
